US00D900511S

(12) **United States Design Patent** (10) **Patent No.:** **US D900,511 S**
(45) **Date of Patent:** **** Nov. 3, 2020**

(54) **DISPLAY STAND**

- (71) Applicant: **Sonos, Inc.**, Santa Barbara, CA (US)
(72) Inventors: **Ran Feder**, Santa Barbara, CA (US);
Andrew Clark, Santa Barbara, CA (US); **Julia Jeanguenat**, Santa Barbara, CA (US); **Mike Ely**, San Francisco, CA (US)
(73) Assignee: **Sonos, Inc.**, Santa Barbara, CA (US)

(**) Term: **15 Years**

(21) Appl. No.: **29/619,708**

(22) Filed: **Sep. 30, 2017**

(51) **LOC (12) Cl.** **20-02**

(52) **U.S. Cl.**

USPC **D6/672**

(58) **Field of Classification Search**

USPC D6/672, 675, 675.1, 675.3, 675.4, 681,
D6/705

(74) *Attorney, Agent, or Firm* — KPPB LLP

(57) **CLAIM**

The ornamental design for a display stand, as shown and described.

DESCRIPTION

FIG. 1 is a front elevation view of a display stand, according to a first embodiment of the invention.

FIG. 2 is rear elevation view of the first embodiment.

FIG. 3 is a first side elevation view of the first embodiment.

FIG. 4 is a second side view of the first embodiment.

FIG. 5 is a top plan view of the first embodiment.

FIG. 6 is a perspective view of the first embodiment.

FIG. 7 is a front elevation view of a display stand, according to a second embodiment of the invention.

FIG. 8 is rear elevation view of the second embodiment.

FIG. 9 is a first side elevation view of the second embodiment.

FIG. 10 is a second side view of the second embodiment.

FIG. 11 is a top plan view of the second embodiment; and, FIG. 12 is a perspective view of the second embodiment.

The features shown in broken lines do not form part of the claimed design.

1 Claim, 10 Drawing Sheets
